JOHN R. BLAKESLEE, OF CLEVELAND, OHIO, ASSIGNOR TO THE AJAX MANUFACTURING COMPANY, OF CLEVELAND, OHIO, A CORPORATION OF OHIO.

METAL WORKING

Application filed February 16, 1925. Serial No. 9,463.

The present improvements have more particular regard to the hot working of metal as in forging and upsetting machines, the object being the provision of an improved 5 method and apparatus for forming socketed articles such as the heads of socket wrenches and the like from solid bar stock.

To the accomplishment of the foregoing and related ends, the invention, then, consists 10 of the steps and means hereinafter fully described and particularly pointed out in the claims, the annexed drawing and the following description setting forth in detail certain means and one mode of carrying out the invention, such disclosed means and mode illustrating, however, but one of various ways 15 in which the principle of the invention may be used.

In said annexed drawing:—

Fig. 1 is a transverse longitudinal section 20 showing the arrangement of dies and heading tool with stock in place in such dies, wherefrom articles of the character referred to may be successively formed, each complete in a single operation; Fig. 2 is a front elevational 25 view of such stationary die and the cutter holder carried thereby, as thus shown in section in Fig. 1; Fig. 3 is a side elevation of such stationary die and cutter holder as viewed from the left in Fig. 2; Fig. 4 is a 30 front elevation, similar to that of Fig. 2, showing the movable die part or cutter; Fig. 5 is a side elevation of the finished article which consists of a socketed wrench head 35 which the foregoing dies and heading tool are adapted to form; Figs. 6 and 7 are end views of such finished article, viewing the same from the right and left, respectively, in Fig. 5; and Fig. 8 is a plan view, on a 40 smaller scale, of the parts shown in Fig. 1, but showing the dies as split on a different vertical plane.

The present machine in its general features is the same as the machine ordinarily used 45 for making rivets, bolts, spikes and the like,

and it is accordingly deemed unnecessary to show either the supporting bed for the die, which includes a stationary part 1 and a movable part or cutter 2, or the mechanism whereby such movable die part or cutter holder 2 and the holder 3 for the heading tool 4 are 50 respectively actuated.

Said stationary die 1 is attached to or otherwise fixedly mounted in front of a block 5 with which the movable cutter holder 2 contacts, such holder being transversely reciprocable from the position shown in Fig. 1 so as to clear, when desired, the opening 6 in the stationary die part 1 when the stock is advanced and the block 5 being formed with an opening 7 aligned with such opening 6 through which such stock may be fed. Upon return of the cutter holder to its closed position, its inner end 8 cuts or shears off a pre-determined length of the rod or bar (not 60 shown) which has been advanced and carries same into alignment with the recess 9 in the stationary die where the upsetting or forming operation takes place. The form and dimensions of this recess correspond with 65 the external form and dimensions of the article which is to be made, such article, as illustrated, being a wrench head 10 which, as shown in detail in Figs. 5, 6 and 7, is of cylindrical shape with an internal socket 10^a 70 of hexagonal cross-section and is provided with a projecting shank 10^b of square cross-section. The rearward extension 11 of recess 9, which serves to form such shank 10^b, extends entirely through stationary die 1, 75 being closed by the forward end 12 of a kicker rod 13 which is reciprocably mounted in an opening 14 that extends through block 5. The portion 15 of this opening immediately 80 back of such recess extension 11 is enlarged to receive a corresponding enlargement 16 on said rod 13, the result of the construction being that in the position of parts shown in Fig. 1 the forward end of said kicker rod is 85 maintained in proper position to close the 90

rear end of recess extension 11 by engagement of such enlargement 16 with the back wall of the opening or chamber 15.

The main portion or body of punch 4 is of the same cross-sectional form as recess 9 and the end 8 of the cutter is of complementary concave form so that in conjunction with the opposed portion of the stationary die 1, such body 4 of the punch is completely enclosed about. The forward end 17 of the punch is of the same cross-section and otherwise of the same form as the socket opening 10^a which it is desired to produce in the finished article.

The complete cycle of operations of the mechanism may now be set forth. Assuming the punch holder 3 to be retracted so as to completely withdraw the punch 4 with its extension 17 from the opening or recess 9 in the stationary die 1, and the cutter holder 2 to be similarly retracted so as to clear the stock feed opening 6, a measured length of stock is advanced beyond the forward end of such last mentioned opening. Thereupon cutter holder 2 is closed with the result, as already explained, that the projecting portion of the stock is cut off and carried into position in recess 9. The kicker rod 13 at this stage is completely retracted, as shown in Fig. 1, and thereupon the punch holder is advanced so as to force the punch 4 with its extension 17 against the approximately cylindrical piece of stock previously placed there. As a result the central portion of such stock is longitudinally displaced to fill the extension 11 of recess 9, while the lateral portions of such piece of stock are held tightly confined between the forward end of the main body of the punch and the surrounding walls of recess 9. It will accordingly be seen that by a single operation of the punch an article of the sort shown in Figs. 5, 6 and 7 is completely fashioned, the shank being formed from the metal thus displaced from the head of the article so as to leave the desired socket recess in the latter. Upon the punch being now retracted to clear the die for a second operation, the kicker rod 13 is simultaneously advanced and the forward portion 12 thereof serves to eject the finished article from the die. At the same time the cutter holder 2 may be withdrawn, the operation of the three moving parts being synchronized so that no time is lost in cutting off and placing a fresh portion of stock in the die recess 9 after the latter has been thus cleared of the previously formed article.

A small passage or duct 20, controlled by a ball valve 21 or the like, preferably leads from the forward end of chamber 15, wherein the enlarged portion 16 of the kicker rod reciprocates, so as to permit lubricant to be introduced therein, and a vent opening 22 (see Fig. 8) may also be provided in the fixed die part 1, such opening communicating

with the extension 11 of recess 9 and serving to permit the escape of any air that may be caught in such recess extension. This last mentioned vent, however, is not essential for the air will ordinarily readily escape past the forward end of the kicker bar. The line of division between the stationary and movable die parts 1 and 2 may be on a different plane from that shown in Fig. 1 without affecting the mode of operation. Thus, as shown in such last mentioned figure, it may be aligned with the rear or inner end of recess 9, the stationary die 1' forming a part of the boundary of the recess and the movable element 2' completing the same.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:—

1. In mechanism for making socketed metal articles of the character described, the combination of a die comprising relatively movable members and having a recess of the dimensions of the body of an article to be formed and an opening parallel thereto for the feed of stock, said members having shearing edges whereby on movement of one a blank is sheared from stock projecting through such opening and is fed to the recess, and means for displacing stock from the middle of such blank back beyond said body recess, said means including a heading tool adapted to enter the recess and having a reduced end, and a port at the rear of said body recess for receiving the stock displaced from the middle of such blank.

2. In mechanism for making socketed metal articles of the character described, the combination of a die having a recess of the dimensions of the body of an article to be formed, a kicker rod at the base of such recess, a valve-controlled duct leading to said kicker rod, means including said die for shearing and feeding a blank of metal to the die recess, and means for displacing stock from the middle of such blank back beyond said body recess, said means including a heading tool adapted to enter the recess and having a reduced end, and a port at the rear of said body recess for receiving the stock displaced from the middle of such blank.

3. In mechanism for making socketed metal articles of the character described, the combination of a die comprising relatively movable members and having a recess of the dimensions of the body of an article to be formed and an opening for the feed of stock, said members having shearing portions whereby a blank is sheared from stock projecting through such opening and is fed to the recess, a kicker rod at the base of such

recess, a valve-controlled duct leading to said kicker rod, and means for displacing stock from the middle of such blank back beyond said body recess, said means including a heading tool adapted to enter the recess and having a reduced end, and a port at the rear of said body recess for receiving the stock displaced from the middle of such blank.

Signed by me this 12th day of February,
10 1925.

JOHN R. BLAKESLEE.
